UNITED STATES PATENT OFFICE.

WILLIAM F. MARKHAM, OF PLYMOUTH, MICHIGAN.

DESIGN FOR A FRAME FOR PISTOLS.

SPECIFICATION forming part of Design No. 24,448, dated July 2, 1895.

Application filed April 11, 1895. Serial No. 545,400. Term of patent 7 years.

to all whom it may concern:

Be it known that I, WILLIAM F. MARKHAM, a citizen of the United States, residing at Plymouth, in the county of Wayne and State of Michigan, have invented and produced a new and original Design for Pistols, of which the following is a specification, reference being had therein to the accompanying drawings.

In said drawings, Figure 1 is a side elevation of a pistol-frame embodying my design, and Fig. 2 is an end elevation thereof.

L represents the stock, which is of substantially rectangular shape, having its corners and edges rounded off, as clearly shown in the drawings. Above the grip portion the sides of the stock are bowed inwardly in graceful curves, as at J, which meet the grip portion of the stock in the rounded corners K.

I is the top of the handle, which is gradually curved and merges at its forward upper

end into the cylindrical barrel A. The under side of the portion I extends forward in the upwardly-inclined section F, which terminates about midway the barrel and presents the projections E on either side thereof.

The barrel A has the rounded end B.

The leading feature of my design is the novel shape and contour of the frame, as above described and as shown in the accompanying drawings.

What I claim as my invention is—

The design for a pistol frame substantially as herein shown and described.

In testimony whereof I affix my signature in presence of two witnesses.

WILLIAM F. MARKHAM.

Witnesses:

M. B. O'DOGHERTY,
O. F. BARTHEL.
